DOUBLE PARABOLIC CYLINDER PENCIL BEAM ANTENNA

Roy C. Spencer, Arlington, Mass.

Application November 20, 1953, Serial No. 393,527

6 Claims. (Cl. 343—837)

(Granted under Title 35, U. S. Code (1952), sec. 266)

The invention described herein may be manufactured and used by or for the Government for governmental purposes without payment to me of any royalty thereon.

This invention relates to microwave antennas and particularly to such antennas for projecting a narrow beam of radiant energy from a point source.

The usual microwave beam antenna allows energy from a point source to reflect from a paraboloid of revolution so that the outgoing energy travels in lines parallel to the axis of revolution of the paraboloid. The antenna forming the subject matter of this invention produces a similar beam of energy, however, instead of using a paraboloid of revolution as a reflector, use is made of successive reflections from two parabolic cylinders with straight-line elements at right angles, each cylinder collimating the beam in one plane. 30

An advantage of this design is that the reflecting surfaces may be simply and inexpensively stamped or cut from flat sheets, with packaging, storage and shipment being facilitated by the flat form of the reflecting cylinders. A further advantage of the design is the possibility of independent control of the vertical and horizontal beam widths. The beam from a point source can be broadened by warping the reflector slightly. The reflector with horizontal straight-line elements controls the vertical beam width and the reflector with vertical straight-line elements controls the horizontal beam width. A second method of controlling the beam width is to change the relative position of the feed and one of the reflectors.

Although this invention particularly relates to microwave antennas the principles involved are equally applicable to light reflectors.

The invention will be described in more detail in connection with the specific embodiment thereof shown in the accompanying drawings, in which

Fig. 1 shows the geometry of the antenna reflecting surfaces;

Figs. 2 and 3 show the developed curves of intersection in each surface, and

Figs. 4, 5, 6 and 7 show various views of a practical embodiment of the antenna.

Referring to Fig. 1, this figure shows a perspective view of the two parabolic cylinders making up the antenna reflectors. The first cylindrical surface S_1 is given by the equation.

$$(1) y^2 = 4fx = 2Lx$$

where f is the focal length and $L=2f$ is the semilatus rectum. The point F with coordinates $(f, 0, 0)$ lies on the focal line of S_1 . The line DD' is the image of the point F in S_1 , that is, any ray emitted from F and incident on S_1 at P_1 is reflected as though it originated on DD' .

The formula for the second cylindrical surface S_2 is given by the equation:

$$(2) (x+f)^2 = 4f(z+f)$$

This surface is so oriented that: (1) its focal line coincides with DD' , (2) it contains the point F , and (3) any ray emitted radially from DD' is reflected parallel to the positive z axis. Under these conditions, S_2 has the same focal length as S_1 , and the point V , with coordinates $(-f, 0, -f)$ lies on the vertex line HH' of S_2 .

It is evident, therefore, that any ray FP_1P_2 emitted from a point source located at F will, after successive reflections from S_1 and S_2 , be directed parallel to the positive z axis. If either condition (2) or condition (3) on S_2 are relaxed, then other combinations of relative focal lengths and orientations would be possible while still satisfying the condition that the image of F in S_1 coincide with the focal line of S_2 . It is thus possible for the two parabolic cylindrical reflectors to have different focal lengths and for the two surfaces to rotate relative to each other through some small but finite angle about line DD' . It is not necessary for the source point F to lie on S_2 , however, it can be made to do so by appropriate combinations of focal length ratio and rotation of surfaces. Should F fall behind S_2 a suitable opening or window may be cut in S_2 .

The x , y and z coordinates of the intersection of the two parabolic cylinders with $2f=L=1$ have been calculated using Equations 1 and 2. The curve of intersection may be written in the following parametric form

$$x = \frac{t^2}{2}$$

$$(3) \quad y = t$$

$$z = \frac{(t^2+1)^2}{8} - \frac{1}{2}$$

Table 1 below contains numerical values of x , y and z as computed from Equation 3. The range of t (i. e., y) is from 0 to 2 in increments of 0.1.

60 The curve of intersection of the two surfaces S_1 and S_2 is a three-dimensional space curve denoted as C in Fig. 1. If the surfaces S_1 and S_2 are separately developed into planes, the intersection curve in each case becomes a plane curve. However, these two plane curves are not identical. In the construction of the double cylindrical reflector, it is desirable to know the coordinates of these plane curves so that they may be laid out on flat sheets before the sheets are bent into the parabolic cylindrical shape.

65 Curves of $z=\text{constant}$ in the surface S_1 are all identical

parabolas and s_1 is defined to be the arc length along any of these parabolas as measured from the z axis (see Fig. 1). Similarly, the curves of $y=\text{constant}$ in the surface S_2 are all identical parabolas and s_2 is defined to be the arc length along any of these parabolas as measured from the vertex line HH' . Table 1 gives the x , y and z coordinates of the intersection curve C . In order to obtain the s_1 , z coordinates of C as measured in the surface S_1 , it is necessary to determine s_1 as a function of either z or y , i. e., the arc length of a parabola as a function of its coordinates. Similarly, in order to obtain the s_2 , y coordinates of C as measured in the surface S_2 , it is necessary to determine s_2 as a function of either x or z . The last two columns of Table 1 give parabolic arc lengths as taken from Air Force Cambridge Research Center Report No. E4083, July 1951, "A Table of Normalized Parabolic Coordinates and Arc Lengths," by R. C. Spencer and G. E. Reynolds.

The straight-line elements of the cylinder S_1 along which the z coordinate is measured, together with the parabolas along which s_1 is measured, form an orthogonal curvilinear coordinate system on the surface S_1 . When the cylinder is developed into a plane, this coordinate system becomes a rectangular system in the plane. The s_1 , z coordinates of the intersection curve C are given in Table 1 and a plot of this curve on the developed surface S_1 is shown in Fig. 2. Similarly, the cylinder S_2 contains an s_2 , y orthogonal curvilinear coordinate system that becomes a rectangular system when S_2 is developed into a plane. The s_2 , y coordinates of the curve of intersection are given in Table 1 and a plot of this curve on the developed surface S_2 is shown in Fig. 3. Note that certain points along the intersection curves, as shown in Figs. 2 and 3, are numbered according to the first column of Table 1. When the developed surfaces S_1 and S_2 are returned to their parabolic cylindrical form and fitted together, identically numbered points will coincide.

A practical embodiment of an antenna constructed in accordance with the foregoing principles is shown in Figs. 4, 5 and 6 in assembled form. Fig. 7 shows the antenna disassembled which illustrates the advantages of the design from the standpoints of packaging, shipping and storing.

The assembled antenna comprises two V-shaped side pieces 1 and 2 separated on one side by struts 3, 4 and 5 and on the other by parabolically curved struts or ribs 6 and 7. The ends of the struts and ribs are provided with dowel pins which pass through openings in the side pieces and are fastened by slide fasteners 8 as shown. The two longer legs of the V-shaped side pieces 1 and 2 are provided with slots 9 and 9' which conform to a parabolic curve. These slots receive the edges of the sheet metal reflector S_2 and hold it in parabolic cylindrical form with the straight-line elements of the reflecting surface normal to the slots. Reflector S_2 is held in position by reflector support bar 10 and locking screw 11 which passes through a hole in S_2 (Fig. 7). The bar 10 is held in position between the side pieces 1 and 2 by dowels located in its ends. The two shorter legs of the side pieces are provided with straight slots 12 and 12' for receiving the edges of the sheet metal reflector S_1 . The length of this sheet of metal is such that when its edges are in the slots it is held in parabolic cylindrical form with the straight-line elements of the reflecting surface parallel to the slots. The inner edges of ribs 6 and 7 are curved parabolically to conform to the shape of reflector S_1 . The horn feed and wave guide assembly 13 is removably attached to struts 4 and 5 by means of dowel pins and slide fasteners, the horn extending through an opening in S_2 .

I claim:

1. A radiator comprising a pair of parabolic cylindrical reflecting surfaces S_1 and S_2 ; said surfaces being positioned relative to each other so that their straight-line elements are at right angles and so that the focal line of S_2 coincides with the image in S_1 of a point F on the focal line of S_1 ; and a point source of radiant energy located at F and directed toward S_1 .
2. A radiator comprising a pair of parabolic cylindrical reflecting surfaces S_1 and S_2 having equal focal lengths; said surfaces being positioned relative to each other so that their straight-line elements are at right angles, so that the focal line of S_1 intersects S_2 at a point F , and so that the focal line of S_2 coincides with the image of the point F in S_1 ; and a point source of radiant energy located at F and directed toward S_1 .
3. A radiator comprising a pair of intersecting parabolic cylindrical reflecting surfaces S_1 and S_2 having equal focal lengths; said surfaces being positioned relative to each other so that their straight-line elements are at right angles, so that the focal line of S_1 intersects S_2 at a point F , and so that the focal line of S_2 coincides with the image of the point F in S_1 ; and a point source of radiant energy located at F and directed toward S_1 .
4. A radiator structure comprising a pair of V-shaped side pieces and strut members therebetween for supporting said sides in parallel spaced relation; means providing a pair of oppositely disposed slots in one pair of oppositely disposed legs of said V-shaped sides, said slots conforming to the curve of a parabola; means providing a pair of oppositely disposed straight slots in the other pair of oppositely disposed legs of said V-shaped sides; said slots in both pairs of oppositely disposed legs lying inside said strut members; a first sheet of metal supported at the edges by said parabolic slots and held in parabolic cylindrical form thereby with the cylindrical straight-line elements normal to and terminating in said parabolic slots; a second sheet of metal supported at the edges by said straight slots, the dimension of said second sheet at right angles to said straight slots being greater than the distance between said straight slots, and the struts behind said straight slots being shaped in the form of a parabolic curve; so that said second sheet is pressed against said curved struts to form a parabolic cylindrical reflecting surface the straight-line elements of which are parallel to said straight slots; and a point source of radiant energy located on the concave side of said second sheet and directed toward said reflecting surface.
5. Apparatus as claimed in claim 4 in which said source of radiant energy is the open end of a waveguide.
6. Apparatus as claimed in claim 4 in which said point source is located at a point on the focal line of said reflecting surface formed by said second sheet and in which the shape of said parabolic slots, the width of said second sheet and the shape of said curved struts, and the angle of said V are such that the focal line of the surface formed by said first sheet coincides with the image of said point of location of said source with regard to the reflecting surface formed by said second sheet.
